UNITED STATES PATENT OFFICE.

CLARENCE A. PHELPS AND JOHN C. GOLLER, OF PITTSBURGH, PENNSYLVANIA.

FLUID-FUEL FILTER.

1,124,166.

Specification of Letters Patent.

Patented Jan. 5, 1915.

Application filed August 26, 1914. Serial No. 858,698.

To all whom it may concern:

Be it known that we, CLARENCE A. PHELPS and JOHN C. GOLLER, citizens of the United States, residing at Pittsburgh, in the county of Allegheny and State of Pennsylvania, have invented certain new and useful Improvements in Fluid-Fuel Filters, of which the following is a specification.

This invention relates to improvements in filters and to such as are particularly adapted for the straining of the fuel of internal combustion engines.

The primary object in view is the removal of all aqueous and foreign substances from the fluid fuel, and a further object is the easy disposal of such removed foreign substances.

With these and further objects in view, as will in part hereinafter become apparent, and in part be stated, the invention comprises certain novel constructions, combinations, and arrangements of parts as subsequently specified and claimed.

In the accompanying drawing: Figure 1 is a longitudinal, vertical, central section of an apparatus embodying the features of the present invention. Fig. 2 is a transverse section therethrough taken on the plane indicated by the line 2-2 of Fig. 1 and looking in the direction of the arrow. Fig. 3 is a view similar to Fig. 1 of the central section and one terminal section, the parts being shown in the position assumed while being supported.

Referring to the drawings by numerals, 1 indicates a tubular central section or chamber having at each end an annular shoulder 2 and an internal thread extending from the shoulder to the respective end of the section, 20 said thread being engaged by a tubular terminal section or chamber 3, there being a terminal section at each end of the central section. A sheet of filtering material preferably chamois skin 4 closes each end portion 30 of section 1 and extends about the shoulder 2 and is engaged and retained in place by an annulus 5, preferably of metal which annulus is engaged by the inner end of the respective terminal section 3 and pressed 40 thereby into clamping engagement with the chamois skin 4, clamping the same against the respective annular shoulder 2. Each annulus 5 may be of any appropriate material, and preferably consists of a metal 50 ring, and each annulus is provided with an axially extended finger 6 formed integral

with or fixed to the annulus and projecting therefrom longitudinally of and within the respective terminal section 3. The free end of each arm 6 is provided with a radial projection or hook 7 disposed to interlock with an annular internal flange 8 formed in each terminal section 3. Each finger 6, when the parts are assembled as indicated in Fig. 1 extends past the respective flange 8 a distance approximately equal to the distance the respective section 3 is threaded into section 1 so that when the terminal section is disconnected from the central section by being unscrewed therefrom, the hook 7 will engage the flange 8 just as the terminal section becomes disconnected from the central section so that the terminal section can be moved laterally or pivotally to the position indicated in Fig. 3 and such movement will cause the upper portion of the ring or annulus 5 to be swung outwardly. Thus the ring is easily loosened and readily removed for enabling removal of the filter 4 for cleansing or renewal.

The intake terminal section 3, that is the section first approached by the gasoline or other fluid fuel, is provided with a drain cock 9 and the central section is provided with a similar drain cock 10, each of the drain cocks being arranged at the lowermost point in the respective section so that water, grit or other foreign substances collecting at the lower portions of the respective sections can be easily drained therefrom.

The operation of the structure is obvious and consists in the supplying of fuel through a pipe 11 into the intake terminal section 3 through the outer closed end thereof from any appropriate source as from the tank of an ordinary automobile. The inflowing fuel penetrates the first filter sheet 4 and passing through the central chamber penetrates the second filter sheet 4 and passes out through the discharge terminal section 3 through a discharge pipe 12 which communicates through the outer closed end of the last-named section 3, said pipe extending to any appropriate point of consumption as, for instance, the carburetor of an ordinary automobile 105 engine.

Aqueous and other foreign substances retarded by the filter 4 are precipitated from the column of fluid fuel always standing in the several sections during use and finding their way to the drain cocks 9 and 10 may be readily removed therethrough. It is ob-

served that the outlet pipe 12 is on a plane at the uppermost portion of the section, and, therefore, in use the several sections are maintained substantially filled with fluid 5 fuel for effecting discharge through pipe 12, so that ample opportunity is afforded for the maintenance of quiet bodies of fluid in which the foreign substances may be precipitated substantially without interruption 10 such as that incident to agitation as would occur in a relatively small rapidly moving column of fluid fuel.

Having thus described our invention, what we claim as new is:

- 15 1. In a fluid fuel filter, the combination of intercommunicating chambers, one of said chambers extending into the other, a sheet of filtering material disposed between the chambers and retained in position by the engagement of one chamber with the other, an annulus directly engaging the peripheral portion of said filtering material, a finger extending from the annulus into one of the chambers, and means in the last-mentioned 20 chamber engaging the finger for withdrawing the annulus when the chambers are separated.
- 25 2. In a fluid fuel filter, the combination of an annular chamber, a second annular chamber threaded into the first, a sheet of filtering material disposed between the inner end of the second annular chamber and

the engaged portion of the first annular chamber, a retaining annulus disposed between said sheet and the inner end of the 35 second chamber, a finger extending axially from the annulus into the second mentioned chamber, and means in the second mentioned chamber engaging the finger for removing the annulus when the second-mentioned chamber is detached from the first. 40

3. In a fluid fuel filter, the combination of an annular chamber, a second annular chamber threaded into the first, a filter sheet dividing the two chambers and having its 45 peripheral portions lying between the inner end of the second chamber and the engaged portion of the first, an annulus between the inner end of the second chamber and the filter sheet, a finger extending axially from the annulus into the second-mentioned chamber and having a hook at its free end portion, and an external annular flange in the second-mentioned chamber adapted to engage the hook of the finger when the second-mentioned chamber is detached from the first. 50 55

In testimony whereof we affix our signatures in presence of two witnesses.

CLARENCE A. PHELPS.
JOHN C. GOLLER.
